OR D 13,550

13 550

JAN 30, 1883

UNITED STATES PATENT OFFICE.

JOHN L. POPE, OF CLEVELAND, OHIO.

DESIGN FOR A HARNESS-BIT.

SPECIFICATION forming part of Design No. 13,550, dated January 30, 1883.

Application filed November 11, 1882. Term of patent 14 years.

To all whom it may concern:

Be it known that I, JOHN L. POPE, of Cleveland, in the county of Cuyahoga and State of Ohio, have invented and produced a new and original Design for Harness-Bits, of which the following is a specification, reference being had to the accompanying photograph, making a part thereof.

My invention relates to a new design for the cheek-piece of harness-bits; and it consists in features of configuration and ornamentation which will be hereinafter more particularly described, and set forth in the claims.

In the photographic illustrations which accompany this specification, Figure 1 represents what is known as a "half-cheek" snaffle-bit, while Fig. 2 represents what is called a "full-cheek" snaffle-bit—that is to say, a bit in which are employed two cheek-pieces projecting from both sides of the bit proper.

In both views the same letters of reference will be used to designate the same parts.

A is the mouth-piece or bit. B B are the rings or loops, and C C the "cheek-pieces," so called.

The cheek-pieces proper will be found to be identical in both views, and, as shown, may be employed in either a half-cheek or full-cheek bit, as well as in a bit having rings or loops of different designs.

My novel design of cheek-piece, as seen in

either illustration, is composed of two portions, D and E, the former lying adjacent to the bit and ring, and being made up of a neck portion and two curved side bars, between which is formed in outline a heart-shaped figure, easily discernible in the photographs. Made integral with this portion D is the part E, composed of open-work. In outline this part is substantially in the shape of a pear, and bears two little projections, *i i*, on the outer edges, from opposite which projections, inside the pear-shaped frame, run outwardly two curved bars, *o o*, which join an eye, *n*, near the extremity of the cheek-piece.

What I claim as new, and desire to secure by Design Letters Patent, is—

1. A harness-bit the cheek-pieces of which are designed substantially as shown.

2. A harness-bit the cheek-pieces of which are composed of frames shaped substantially as D and E.

3. A harness-bit the cheek-pieces of which are composed of frames, such as D and E, and the latter provided with the curved bars *o o* and eye *n*.

In witness whereof I have hereunto set my hand this 3d day of November, 1882.

JOHN L. POPE.

In presence of—

WALTER A. BIDDLE,
GEORGE F. EBERHARD.
